The ornamental design of a utility knife, as shown and described.

DESCRIPTION

FIG. 1 is a perspective view of a utility knife showing my new design, wherein the broken line showing of the blade holding mechanism is in the unfolded position.

FIG. 2 is a top view thereof.

FIG. 3 is a side view thereof.

FIG. 4 is a front view thereof.

FIG. 5 is a rear view thereof.

FIG. 6 is a bottom view thereof.

FIG. 7 is another side view thereof.

FIG. 8 is a side view thereof, wherein the broken line showing of the blade holding mechanism is in the partially folded position; and,

FIG. 9 is a side view thereof, wherein the broken line showing of the blade holding mechanism is in the folded position.

The broken line portions of the disclosure are for illustrative purposes only and form no part of the claimed design.
